[57] CLAIM

The ornamental design for a license plate holder as shown.

DESCRIPTION

FIG. 1 is a front elevational view of a license plate holder showing my new design;

FIG. 2 is a top plan view thereof, the bottom being substantially a mirror image of the top shown herein; FIG. 3 is a side elevational view thereof, the opposite side being substantially a mirror image of the side shown herein;

FIG. 4 is a sectional view thereof taken along the line 4—4 of FIG. 1; and

FIG. 5 is an enlarged fragmentary plan view of the portion of the license plate frame shown within the circle 5 of FIG. 1.
